UNITED STATES PATENT OFFICE.

LOUIS B. SAMMIS, OF WALLACE, AND FRANK R. HOOD, OF BURSON, CALIFORNIA.

GRADER.

Application filed May 26, 1924. Serial No. 715,842.

To all whom it may concern:

Be it known that we, LOUIS B. SAMMIS and FRANK R. HOOD, citizens of the United States, residing at Wallace and Burson, respectively, county of Calaveras, State of California, have invented certain new and useful Improvements in Graders; and we do declare the following to be a full, clear, and exact description of the same, reference being had to the accompanying drawings and to the characters of reference marked thereon, which form a part of this application.

This invention relates to improvements in grading devices, and particularly to one especially intended for grading olives, though it may be made in different sizes, or adjusted, to grade any fruit or other produce which is either round or has an oblong shape similar to an olive.

The principal objects of our invention are to provide a grader for the purpose so designed that olives etc. of all varieties and sizes may be accurately graded, so as to give a correct count per pound; the olives are not subjected to any violent shaking or handling such as would bruise them; and the different grades of produce are kept separate from each other. The device is also very economical to operate and adjust.

In connection with the grading device proper, we have applied a sorting belt structure, by means of which all culls and imperfect fruit may be removed before the fruit is passed to be graded.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Fig. 1 is a longitudinal sectional elevation of the grader.

Fig. 2 is a top plan view of the same.

Fig. 3 is a typical cross section of the device.

Fig. 4 is a more or less diagrammatic plan view of the endless belt arrangement used.

Referring now more particularly to the characters of reference marked on the drawings, the numeral 1 denotes the horizontal

sorting belt, of suitable length and divided into three transversely disposed sections by means of longitudinal partitions 2 fixed just above the upper run of the belt. A hopper 3 discharges onto the middle section of the belt at one end thereof, the belt moving away from the hopper. At the other end of said belt discharge chutes 4 lead downwardly from the side sections of the belt, 65 while an apron 5 leads from the center section to the grader proper.

This structure comprises a suitable supporting framework 6 in which are journaled a pair of shafts 7 and 8, in suitable horizontally spaced relation. On the shaft 7, which is under the apron, is a plurality of sheaves 9, one only of which is fixed on the shaft, the others being turnable thereon. Said shaft preferably has a pulley 10 or the like 75 on one end, so that it may be driven by suitable power means.

Loose on the shaft 8, but held against longitudinal movement thereon, are sheaves 11 of the same size and to the same number as the sheaves 9, but spaced further apart than the latter, this spacing being made adjustable by any suitable means. An endless cable 12 passes over all the sheaves, preferably in the manner shown in Fig. 4, 85 so that the upper runs of the cable all travel in the same direction and away from the apron 5. The cable is driven from the single fixed sheave on the shaft 7, and is kept at a suitable tension by means of a spring- 90 pulled and adjustable tightener structure shown at 13 in Fig. 4 and acting on that lower run of the cable which extends between the opposite sheaves on the two shafts. The cable being a single length, the tightener applied to this one run of course maintains the entire cable at a common tension. Suitable spacer rollers 14, to keep the cables from spreading between the sheaves, are 95 disposed under the upper runs of the cable 100 at certain intervals. It will thus be seen that said upper runs, due to the uneven spacing of the sheaves 9 and 11, form a series of slots of gradually increasing width from end to end, the slots being narrowest at the 105 apron 5.

Loosely suspended from longitudinally spaced supports 15 mounted above the upper cables and extending across the same are fingers or pins 16, directly above the 110 various cables and terminating just clear of the same.

These pins cannot drop further down, but have considerable freedom of lateral swinging movement about their upper ends as an axis or fulcrum.

5 Mounted under the upper cable runs but above the lower ones is a longitudinal tray 17 having a transverse downward slope from one side to the other, and projecting at one side outwardly of the plane of the 10 cables, as shown in Fig. 3. A plurality of longitudinally spaced discharge spouts 18 lead downwardly from the lowest level of the tray.

This tray is adjustably divided into the 15 same number of compartments as there are spouts, by means of vertical partitions 19 extending transversely thereof. These partitions are detachably connected to the upper side of the tray by means of lugs 20 on the partitions which fit into any at a time of a number of suitably disposed slots 21 in the upper side-wall 17^a of the tray. Onto the opposite ends of the partitions are hinged vertical plates 22 which have sliding and telescopic connection with similar plates 23 themselves permanently hinged onto the lower side wall 17^b of the tray between the spouts 18. The hinge pins 24 of the plates 22 project below the same and are 10 adapted to seat in holes 25, in the bottom of the tray, these holes being in transverse alignment with the slots 21.

By means of this construction, the longitudinal setting of any partition in the tray 35 may be altered one way or the other, so as to alter the relation of the partitions to the width of the spaces or slots between the cables above, and increase or decrease the spacing between any two partitions. At the 40 same time, the fruit between any two partitions will always discharge from the same spout 18, since the lower ends of the partition structures are permanently fixed.

The number of partitions employed 45 determines the number of grades or sizes of the fruit, while their setting relative to each other and to the cables determines the size of each grade and consequently the count per pound of fruit.

50 The hinged telescoping plate arrangement enables a continuous partition to be maintained between a fixed point at the lower side of the tray, and an adjustable point at the upper side thereof, while allowing the main partitions 19 to be kept in a direct transverse plane.

In operation, the olives as they come from the orchard are placed in the hopper 3, from 60 which they pass by gravity onto the sorting belt 1. Here the olives are sorted, the culls etc. being placed on the side sections of the belt and being discharged therefrom into the chutes 4. The olives are also stemmed at this time. The fruit remaining on the belt passes over the apron 5 onto the grad-

ing cables 12, which travelling away from the apron, carry the olives along until the width of the slots between the cables is sufficient to allow the olives to drop therethrough into the tray beneath. The larger 70 the olives, the further they will travel before dropping through, and any too large to pass through at all, are carried over an apron 26 beyond the sheaves 11.

In grading olives, their diameter rather 75 than their length is considered, and since most olives are oblong they sometimes tend to ride crosswise of the cables. The fingers 16 act to turn the olives so that they ride lengthwise of the cables, or so that trans- 80 verse axis is at right angles to the cables. By reason of the fact that these fingers are flexibly hung, they will not damage or bruise the fruit in any way, large olives merely causing the fingers to spread laterally so as to enable said olives to pass by. The rollers 14, as well as the various 85 sheaves, are concaved between the cables, so as to cause the olives to be supported by the cables at all times, and enabling them to 90 maintain the lengthwise position thereof on the cables.

From the foregoing description it will be readily seen that we have produced such a device as substantially fulfills the objects of 95 the invention as set forth herein.

While this specification sets forth in detail the present and preferred construction of the device, still in practice such deviations from such detail may be resorted to 100 as do not form a departure from the spirit of the invention, as defined by the appended claims.

Having thus described our invention what we claim as new and useful and desire to secure by Letters Patent is:

1. A grader including sheaves arranged in longitudinal sets, the sheaves of one set being spaced transversely a different distance from those of the other set, and a single endless driven cable passed about all the sheaves.

2. A grader including sheaves arranged in longitudinal sets, the sheaves of one set being spaced transversely a different distance from those of the other set, a single endless cable passed about all the sheaves, the upper runs of said cable being adapted to all move in the same direction and extending between corresponding sheaves of 120 the sets.

3. A grader comprising a plurality of driven cable lengths arranged in a common horizontal plane and diverging from each other from end to end, a tray under said cables, discharge openings at intervals in the length of the tray, longitudinally adjustable partitions in the tray between the spouts and extending transversely of the cables, and means whereby fruit dropping 125 130

from between the cables into the tray-area between any two partitions therein will always be diverted to the same opening regardless of the adjustment of the partitions.

5. A grader comprising a plurality of driven cable lengths arranged in a common horizontal plane and diverging from each other from end to end, a tray under said cables, discharge openings at intervals in the 10 length of the tray, longitudinally adjustable partitions in the tray extending transversely of the cables, and auxiliary partitions flexibly connected at one end to the first named partitions and similarly but permanently 15 connected at their other ends to the tray between the opening.

5. A grader comprising a plurality of driven cable lengths arranged in a common horizontal plane and diverging from each 20 other from end to end, the fruit to be

graded being adapted to be placed on said cables at the end thereof closest together, and pins arranged for limited universal movement being directly above the cables in transverse alignment therewith and terminating clear of the same. 25

6. A grader comprising a plurality of driven cable lengths arranged in a common horizontal plane and diverging from each other from end to end, the fruit to be 30 graded being adapted to be placed on said cables at the end thereof closest together, and flexibly hung pins directly above the cables at spaced intervals in the length 35 thereof.

In testimony whereof we affix our signatures.

LOUIS B. SAMMIS.
FRANK R. HOOD.
